UNITED STATES PATENT OFFICE.

JAY C. STONE, OF SPOKANE, WASHINGTON.

MECHANICAL MOVEMENT.

1,407,233.

Specification of Letters Patent. Patented Feb. 21, 1922.

Application filed May 2, 1921. Serial No. 466,132.

To all whom it may concern:

Be it known that I, JAY C. STONE, a citizen of the United States, residing at Spokane, in Spokane County and State of Washington, have invented certain new and useful Improvements in Mechanical Movements, of which the following is a specification.

My present invention relates to improvements in mechanical movements designed particularly for converting the reciprocating motion of a driving mechanism to a rotary motion through the medium of intermediate, oscillating mechanism and lever connections, whereby the driving of the driven shaft may be accomplished with ease, regularity and with the elimination of danger of a dead center occurring in the movement of the parts. For this purpose the mechanical movement is well adapted for use in connection with various power plants, as for instance a wind-mill or other motor operated by fluid currents.

The invention consists essentially in certain novel features of construction involving an oscillatable, power-transmitting lever interposed between the reciprocating part and the rotary parts, and in certain combinations and arrangements of lever arms and connecting links between the oscillating lever and crank shaft for insuring a uniform and facile transmission of power as will be hereinafter more fully described and claimed.

In the accompanying drawings I have illustrated one complete example of the physical embodiment of my invention wherein the parts are combined and arranged according to the best mode I have thus far devised for the practical application of the principles of my invention.

Figure 1 is a view in side elevation of the mechanism involving my invention, part of the oscillating lever being shown in section for convenience of illustration.

Figure 2 is a top plan view of the mechanism of Figure 1.

Figure 3 is a face view of the crank disk or wheel on the driven shaft.

Figure 4 is an edge view of the disk of Figure 3.

Figure 5 is a detail view of one of the lever arm mechanisms looking from the left in Figure 1 as indicated by the arrow.

Figure 6 is an enlarged view, partly broken

away, showing the oscillating lever between the reciprocal and rotary members.

Figure 7 is an edge view of the lever, looking from the right in Figure 6, parts being shown in section.

Figure 8 is a plan view of one of the lever arms.

In the preferred form of the invention as shown in the drawings, the operating parts are supported on a frame 1 of suitable size and shape for the purpose, and in this frame the oscillating lever 2 is journaled at 3. The lever is adapted to swing in a vertical plane and at its upper end a connecting link or rod 4 is pivoted at 4' the link or rod receiving a reciprocating motion in a horizontal direction from a suitable source of power and transmitting this motion to the oscillating lever.

The lever 2 is the medium through which the reciprocal motion of the connecting rod 4 is transmitted to the driven, rotary shaft 5, disposed in a horizontal plane and supported in journal bearings 6 in the frame and provided with a pulley wheel 7 from which power may be taken by a belt to its desired destination and use.

The leverage of the oscillatable lever may be varied by changing the point of application of power thereto and for this purpose the pin 4' connecting the rod 4 with the lever is mounted on a rectangular strap 8 in the form of a metal band movable on the upper end of the lever. The band has attached thereto a rack bar 9 lying parallel with the lever, and a rack wheel 10, journaled in the bracket 11 fixed on the lever, engages this rack bar in order that by turning the hand crank 12 of the wheel, the co-action of the wheel and rack will result in adjusting the strap 8 on the lever to desired position for shortening or lengthening the working stroke of the oscillating lever.

The lever is preferably of metal, rectangular in cross section and hollow for the accommodation of a lever arm 13 encased therein, the arm being adapted to oscillate with the lever, and also being adapted for longitudinal movement therein with relation to the lever, and for this purpose a slot 14 is provided in the movable arm through which the pivot pin 3 is passed.

The longitudinal movement of the lever arm within the lever is guided by means of pairs of laterally disposed guide rollers

15 journaled within the hollow lever and in position for frictional contact with the edges of the movable lever arm, while at the lower extremity of the movable lever arm is journaled an anti-friction roller or wheel 16.

At its lower end the lever is fashioned with an open slot 17 and the movable lever arm within the lever is fashioned with a complementary slot 17', adjacent to the anti-friction roller 16 for a purpose to be described.

At the lower end of the oscillating lever is provided a wrist pin 18 with cap 19 for pivotal connection with a pair of links 20, 21 and a third link 22, each of which is 15 made up in sections joined by a turn buckle 23 in order that the length of these links may be adjusted for correct movement of the parts, and the links are adapted, through a flexible connection to transmit 20 motion to the driven shaft. The flexible connection includes a pair of bell crank levers, one of which 24, is pivoted at 25 in the frame and has its long arm extended into the slots 17 17' of the lever and its 25 movable arm near its extremity engages the anti-friction roller 16 of the movable lever arm at its upper side. The short arm 26 of the bell crank lever 24 has a pin 27 making a pivotal connection with the slotted end 28 of the link 20, and a spring 29 interposed between the long arm of the bell crank lever and the frame tends to hold the extremity of the long arm in contact with the roller 16.

35 At the opposite side of the shaft 5 is located a second bell crank lever 30, pivoted in the frame at 31 and having a pivotal connection at 32 with the slotted end 33 of the link 22, and a spring 34 between 40 the frame and long arm of this lever holds the long arm of the lever against the under side of the anti-friction roller 16.

The third link, 21, also has a slotted connection at 35 and 36 with an angular latch member, and this lever also has an arcuate flange 37 and lug 38 for co-action with a pawl 39 of the latch which is pivoted in the bracket 40 in the frame and provided with a spring 41 to hold the pawl against 45 the flange and force it into contact with the lug 38 for the purpose of positively holding the long arm of bell crank lever 30 when it is raised to its highest point during the period that the wrist pin 18 50 travels the third quarter of its movement and is well into the last quarter.

Thus it will appear that the oscillation of the main lever and its movable arm will, through the wrist pin 18 cause the links 60 20, 21, 22 to reciprocate horizontally, and the action of these links on the bell crank levers will cause said levers, alternately to positively engage the roller 16 forcing down and lifting up the roller and its movable 65 arm with relation to the oscillating main

lever, as indicated in dotted lines in Figure 1. The resulting action of the bell crank levers is a combined up and down movement of the movable lever arm, and the horizontal oscillation of the main lever causes a 70 rotation of the roller end of the movable lever about the shaft 5 as a center.

The shaft 5 has fixed at one end the crank wheel or disk 42, and the wrist pin 43 on the disk affords a journal bearing for the 75 anti-friction roller 16 on the movable arm of the main lever, a slot 44 being provided in the wall of the main lever to accommodate the wrist pin or crank pin of the crank wheel. In Figure 3 particularly, it 80 will be seen that the crank pin is not rigidly carried by the crank wheel, but is supported on a crank arm 45 which is pivoted at 46 to the crank disk, and a spring 47 on the disk tends to urge the crank arm and 85 crank pin away from the disk center or shaft 5, the crank arm having a slotted extension 48 retained by a pin 49 in the disk to allow this movement.

Referring to Figure 1 and assuming the 90 rod 4 to be moved to the right in the direction of the arrow, the main lever and its movable arm are swung on the pivot 3. In this position the wrist pin 18 has reached and passed the extreme of its movement to 95 the right, and the link 20 is urging the bell crank lever 24 to bear upon roller 16 and force the movable lever arm and crank pin downwardly, thus imparting rotary movement to the shaft 5. As the crank pin 100 and roller 16 pass downwardly, and to the left, the action of the lever 24 is completed, and the link 20, because of the slotted connection at 27-28 is pulled to the left in Figure 1 without action of the bell crank 105 lever 24, the latter being held by its spring 29.

As the wrist pin swings to the left from position in Figure 1, the link 22 is pushed to the left until the inner wall of the slotted 110 extension of the link contacts with the pin 32. The bell crank lever 30 is now oscillated on its pivot 31 and the long arm of the lever 30 is swung into engagement with the lower edge of roller 16, and as the roller and crank pin pass through the latter part of the 3rd quarter and the initial part of the 4th quarter of this stroke, the lever 30 lifts the roller, movable lever arm and crank pin, causing rotation of the shaft 5.

To prevent a backward movement or reverse action of the crank pin when passing through the fourth quarter of the revolution of the shaft 5, due to weight of the movable lever arm, the bell crank lever 30 is positively 125 held by action of the pawl 39 on the lug 38 of the bell crank lever, which holds the lever when its long arm is elevated during the period while the wrist pin is traveling through the 3rd quarter of the stroke. Then 130

as the main lever again reciprocates or oscillates and reciprocates the link 22 and oscillates bell crank lever 30, the pawl 39 is withdrawn from lug 38, releasing the bell crank lever.

Any unevenness or irregularity in the rotary action of the crank pin is compensated for by the pivoted crank arm or crank plate 45, which permits the crank pin to alter its relation to the shaft 5 and increase or decrease the leverage to insure a smooth and uniform movement. In this manner the reciprocating movement of the link 4 is converted into rotary movement of the shaft 5 without necessity for use of a fly or balance wheel, the action of the parts is made positive, and a continuous power is transmitted and applied to the crank pin and crank wheel to revolve the shaft 5 with a uniform rotary movement.

Having thus fully described my invention, what I claim as new and desire to secure by Letters Patent is—

1. The combination with a hollow, pivoted lever, and a reciprocating driving member, of a relatively movable lever arm, a driven shaft and a crank connection between said movable arm and shaft, oppositely disposed links connected with said lever, and complementary bell crank levers operatively connected with said links and adapted to alternately co-act with said crank connection between the lever arm and driven shaft.

2. The combination with a hollow, pivoted lever and actuating means, of an internal movable lever arm having slotted connection with the pivoted lever, a rotary shaft and crank connections between said shaft and lever arm, oppositely disposed, extensible links pivoted on said lever, complementary bell crank levers operatively connected with said links, and the long arms of said bell crank levers adapted to alternately engage said crank connections.

3. The combination with a hollow, oscillatable lever and a slotted, longitudinally movable lever arm therein having a crank pin and anti-friction roller thereon, a crank wheel and a rotary shaft, of oppositely disposed links pivoted to said lever, and complementary bell crank levers pivoted to said links with their long arms adapted to alternately engage said roller.

4. The combination with a hollow, oscillatable lever and a slotted, longitudinally movable lever arm therein, a rotary shaft, a crank wheel and a crank pin connecting said lever arm and wheel and an anti-friction roller on said pin within the lever, of oppositely disposed links connected to said lever and provided with slotted extensions, a pair of pivoted bell crank levers connected with said slotted extensions and the long arms of said bell crank levers adapted to pass through slots in the ends of the lever and lever arm to alternately engage said roller.

5. The combination with a hollow, oscillatable lever and a slotted lever arm therein having a crank pin and roller on its end, a rotary shaft, a crank wheel thereon and a crank arm pivoted on said wheel to support the crank pin, of oppositely disposed links pivoted to said lever, and complementary bell crank levers operatively connected with said links with their long arms adapted to alternately engage said roller.

6. The combination with an oscillatable lever and its relatively movable lever arm, of a rotary shaft and crank disk, an eccentrically pivoted crank arm on said disk, a crank pin connecting said arm and lever arm and a roller on said pin, of oppositely disposed links pivoted to said lever, and complementary bell crank levers operatively connected with said links with their long arms adapted to alternately engage said roller.

7. The combination with an oscillatable lever and its relatively, longitudinally movable lever arm having a crank pin thereon, of a rotary shaft, a crank wheel and a crank arm pivoted on said wheel and engaging said pin, and alternately actuated means between said lever and crank pin for rotating said shaft.

8. The combination with an oscillatable lever and its relatively, longitudinally movable lever arm having a crank pin and roller thereon, of a rotary shaft, a crank wheel, a crank arm pivoted on said wheel and engaging said pin, a pair of bell crank levers adapted to alternately engage said roller, and connections between said lever and bell crank levers for actuating the latter.

In testimony whereof I affix my signature.

JAY C. STONE.
